UNITED STATES PATENT OFFICE

101,908

DESIGN FOR A BADGE

Myrtle Weldon and Ida C. Hagman,
Lexington, Ky.

Application August 10, 1936, Serial No. 64,339

Term of patent 7 years

To all whom it may concern:

Be it known that we, Myrtle Weldon and Ida C. Hagman, citizens of the United States of America, residing at Lexington, in the county of Fayette and State of Kentucky, have invented a new, original, and ornamental Design for Badges, of which the following is a specification, reference being had to the accompanying drawing, forming part thereof.

Fig. 1 is a face view of a badge showing our new design and Fig. 2 is a sectional view taken on lines 2—2 of Fig. 1.

We claim:

The ornamental design for a badge, as shown.

MYRTLE WELDON.
IDA C. HAGMAN.
